SWITCH & SIGNAL COMPANY, OF SWISSVALE, PENNSYLVANIA, A CORPORATION
OF PENNSYLVANIA.

CENTRIFUGAL DEVICE.

1,120,252.

Specification of Letters Patent.

Patented Dec. 8, 1914.

Application filed July 25, 1912. Serial No. 711,460.

To all whom it may concern:

Be it known that I, JOHN D. TAYLOR, a citizen of the United States, residing at Edgewood Park, in the county of Allegheny and State of Pennsylvania, have invented 5 certain new and useful Improvements in Centrifugal Devices, of which the following is a specification.

My invention relates to centrifugal devices.

I will describe one form of centrifugal device embodying my invention, and will then point out the novel features thereof in claims.

15 In the accompanying drawings, Figure 1 is a view showing in vertical section one form of centrifugal device embodying my invention, the upper portion of head 11 being shown in elevation. Fig. 2 is a top view 20 of the centrifugal device shown in Fig. 1. Fig. 3 is a view showing in vertical section the upper portion of head 11 shown in Fig. 1.

Similar reference characters refer to similar parts in the several views.

One feature of my invention is the provision of means for preventing rotation of the centrifugal device in one direction, which means is operative while the device 30 is at rest but inoperative while the device is rotating.

Referring to the drawings, the centrifugal device comprises a tubular spindle 4 mounted in a suitable manner (not shown) so that 35 it is free to rotate. This spindle is rotated by suitable means not shown. Extending from the upper end of spindle 4 are two yokes 10 in each of which is pivoted a two-armed lever 9. The downwardly extending 40 arm of each lever carries a weight 8, which weights are thrown outwardly by so-called centrifugal force when spindle 4 is rotated, thereby depressing the other arms of levers 9. The latter arms project into holes 11* 45 in a head 11 which is fixed to a stem 28 which latter reciprocates vertically in the upper end of spindle 4. It will be seen, therefore, that when the balls 8 swing outwardly, the head 11 is drawn down, and that 50 the head rotates with the spindle 4. The head 11 is connected with a link 26 through the medium of a ball-bearing 27, so that this link is reciprocated vertically by the head but does not rotate therewith. As shown

in Fig. 3, the inner race of the ball-bearing 55 is attached to the link 26 by nuts 26^a, and the outer race is clamped between the top of head 11 and an inner flange on a nut 39 which screws on a threaded portion of the head. The upper end of link 26 is pivotally 60 connected to an arm 13 which is attached to a bar 12. The ends of this bar are upturned and are provided with pivot studs 19^a by means of which the bar may be pivotally mounted to swing in trunnion screws 65 19. It will be seen that movements of the balls 8 toward and away from the longitudinal axis of spindle 4 will cause bar 12 to rock in trunnion screws 19. This movement of the bar may be employed to accomplish any 70 desired result. In order to avoid friction, the ball-bearing 27 is constructed to permit of slight lateral movement of the link 26 with relation to head 11, and the stem 28 is capable of slight lateral movement in spindle 4, hence a pin and slot connection between parts 13 and 26 is unnecessary.

So far as the apparatus thus far described is concerned, the centrifugal device is capable of being rotated in either direction. In 80 order to prevent rotation in one direction, I provide a pawl and ratchet device comprising ratchet teeth 55 on the circumference of nut 39, and a pawl 56 fixed to a plate 57 riveted to bar 12. The ratchet device is so 85 arranged that when the bar 12 is in the position corresponding to the position of rest of balls 8, the pawl 56 engages with the teeth 55 to prevent rotation of head 11, and consequently of spindle 4, in one direction, 90 but that when the bar 12 is swung by the outward movement of the balls due to rotation in the other direction the pawl 56 is moved out of the path of teeth 55. Hence, while the centrifugal device is rotating, the 95 pawl 56 does not touch the teeth 55, so that the ratchet device then offers no resistance to the rotation and is noiseless.

Although I have herein shown and described only one form of centrifugal device 100 embodying my invention, it is understood that various changes and modifications may be made therein within the scope of the appended claims, without departing from the spirit and scope of my invention.

Having thus described my invention, what I claim is:

1. In combination, a centrifuge, and

means operative while the centrifuge is at rest for preventing rotation of the centrifuge in one direction, said means being inoperative while the centrifuge is rotating.

5 2. In combination, a centrifuge, a ratchet rotated by the centrifuge, and a pawl moved by the centrifuge and arranged to be in or out of position for engagement with the

ratchet according as the centrifuge is at rest or rotating.

In testimony whereof I affix my signature in presence of two witnesses.

JOHN D. TAYLOR.
